UNITED STATES PATENT OFFICE

143,001

DESIGN FOR A FLEXIBLE BAND FOR A BRACELET OR SIMILAR ARTICLE

Victor Guglielmi, Leonia, N. J.

Application July 7, 1945, Serial No. 120,561

Term of patent 7 years

(Cl. D45—4)

To all whom it may concern:

Be it known that I, Victor Guglielmi, a citizen of the United States, residing at Leonia, in the county of Bergen and State of New Jersey, have invented a new, original, and ornamental Design for a Flexible Band for a Bracelet or Similar Article, of which the following is a specification, reference being had to the accompanying drawing, forming part thereof:

Fig. 1 is a plan view of a flexible band for a bracelet or similar article, the portion shown in full lines being repeated throughout the length of the band.

Fig. 2 is an enlarged detailed front view of a portion of the flexible band shown in Fig. 1.

Fig. 3 is an enlarged detailed front view showing the flexible band in an expanded position.

Fig. 4 is an enlarged end view taken in the direction of the arrows on the lines 4—4 in Fig. 2.

Fig. 5 is an enlarged fragmentary sectional view taken on the line 5—5 of Fig. 3.

I claim:

The ornamental design for a flexible band for a bracelet or similar article, as shown.

VICTOR GUGLIELMI.
